DESIGN FOR A SERVER FOR CIGARETTES OR THE LIKE

Julius Ralph Davidson, Chicago, Ill., assignor to Kensington, Incorporated, New Kensington,
Pa., a corporation of Pennsylvania

Application January 15, 1936, Serial No. 60,605

Term of patent 3½ years

To all whom it may concern:

Be it known that I, Julius Ralph Davidson, a citizen of Germany, residing at Chicago, in the county of Cook and State of Illinois, have invented a new, original, and ornamental Design for a Server for Cigarettes or the Like, of which the following is a specification, reference being had to the accompanying drawing, forming a part thereof.

Fig. 1 is an end view of a server for cigarettes or the like in closed position and embodying my new design;

Fig. 2 is a side view of the same in closed position;

Fig. 3 is a perspective view of the server for cigarettes or the like in partly opened position.

I claim:

The ornamental design for a server for cigarettes or the like, as shown and described.

JULIUS RALPH DAVIDSON.
